UNITED STATES PATENT OFFICE.

RICHARD A. LEADBETTER, OF DETROIT, MICHIGAN, ASSIGNOR TO THE FARRAND COMPANY, OF DETROIT, MICHIGAN, A CORPORATION OF MICHIGAN.

CONTROL MECHANISM FOR SELF-PLAYING MUSICAL INSTRUMENTS.

1,111,799.

Specification of Letters Patent.

Patented Sept. 29, 1914.

Application filed July 16, 1912. Serial No. 709,688.

To all whom it may concern:

Be it known that I, RICHARD A. LEADBETTER, a citizen of the United States of America, residing at Detroit, in the county 5 of Wayne and State of Michigan, have invented certain new and useful Improvements in Control Mechanism for Self-Playing Musical Instruments, of which the following is a specification, reference being had 10 therein to the accompanying drawings.

The invention relates to self-playing musical instruments of the type adapted for either automatic or manual operation, and more particularly to manually and automatically 15 operable pianos.

Instruments of this type are provided with various control devices, such as the tempo, the winding and re-winding control, tracker shifting mechanism for registering 20 the tracker with the music and for transposing the key, pedal control, etc. These controllers are most conveniently arranged at the front of the key bed, but inasmuch as a number of the devices controlled are 25 arranged above the key bed, operating connections must be arranged therebetween. This is difficult because the greater portion of the key bed is covered by the keys, and to pass connections between the keys necessitates the cutting away of the latter to an 30 extent that is objectionable.

With the present invention the controllers are arranged at the front of the key bed and are connected with the respective devices to be controlled by a novel construction 35 and arrangement of intermediate mechanism. Furthermore this mechanism passes from below to above the key bed without interference or requiring modification in the construction of the keys or any other part of the manually operable or automatic action. Still further, the construction is such that the automatic action may be readily attached or detached without dis- 40 assembling the controller mechanism.

In the drawings: Figure 1 is a plan of the key bed showing the arrangement of the various control devices thereon. Fig. 2 is a sectional view of a portion of the 45 bed. Fig. 3 is a cross section. Fig. 4 is a perspective view of the detachable coupler for connecting the mechanism on the fixed and removable portions of the instrument.

In the construction of pianos and other

key actuated musical instruments of the same 55 general type, it is usual to provide a key bed, which forms a rigid support for the keys. There is also a key frame on which the keys are directly fulcrumed, and which is arranged on top of the key bed. The key 60 bed is formed of comparatively heavy longitudinal and cross bars, while the key frame is formed of thin stock, and receives its strength from the bed on which it is supported. As shown, A is the key bed provided with parallel longitudinal bars A' and A'', connected by cross bars A''. B is the key frame which is likewise provided with longitudinal bars B' and B'' in front and rear, with intermediate, longitudinally extending fulcrum bar B''. The latter is usually arranged to extend over the spaces between the bars A' and A'' of the bed, but is supported upon the cross bars A''.

My improved construction of control 75 mechanism comprises a plurality of levers which are supported and fulcrumed upon the key bed below the key frame, which latter is suitably cut away to provide clearance for movement of the levers. As shown, three 80 levers C C' and C'' are thus fulcrumed and arranged, the re-roll lever being fulcrumed at D to the rear bar of the key bed, and passing through a slot E in the fulcrum bar B'' of the key frame. The levers C' and C'' 85 are fulcrumed upon the forward bar of the key bed and terminate in front of the fulcrum bar B''. To connect these levers with the mechanism controlled thereby and without interference with any other part, I employ transversely extending rock shafts F, E' and E'', which are arranged in the space between the forward and rear bars of the key bed. Each of these rock shafts is provided with an upwardly extending rock arm 90 F and a downwardly extending rock arm G, the former being connected by longitudinally extending rods H, which are arranged in front of the fulcrum bar B'' with their respective levers C C' and C''.

The downwardly extending rock arms are connected with rods I, which pass beneath the key bed and extend to one side of the instrument. For extending these operating connections to the devices above the key bed, vertically extending rock shafts J J' are arranged in close proximity to the side of the instrument case, extending upward through

the key bed at a point where they will clear the other devices and being journaled in suitable bearings such as the brackets K. These vertical rock shafts are connected by 5 rock arms L at their lower ends with the rods I, while at their upper ends they are provided with rock arms M.

N are rods connected to the devices to be controlled, such as the shiftable, music-holding frame O and re-wind lever P, both of 10 which are located upon the top of the pneumatic action Q. The rods N are coupled to the rock arms M by a quickly detachable 15 connection, such as the hooked ends R, which pass through eyes in the rock arms, and the spring loops S for engaging said hooks and preventing accidental disengagement. Thus whenever it is desired to remove the pneumatic action it is only necessary to uncouple 20 the hooks R, after which the action may be removed without interference with the control mechanism.

The construction as described is one which is inexpensive to manufacture, is convenient 25 for manipulation, and requires no change in the construction of either the manually operable or automatic action.

What I claim as my invention is:

1. A controlling mechanism for self-playing 30 musical instruments which includes a key bed, a key frame positioned above the bed and keys comprising levers pivotally mounted upon the key bed below the key frame and movable in the plane of the bed, 35 said bed including longitudinal bars, a plurality of bell crank levers supported by said bars, rods connecting the first mentioned levers with the bell crank levers, a plurality of vertically extending bell crank levers having 40 an operative connection with the mechanism to be controlled and connections between the first mentioned bell crank levers and the second mentioned bell crank levers whereby actuation of the first mentioned

levers will operate the bell crank levers to 45 actuate the mechanism to be controlled.

2. A controlling mechanism for self-playing 50 musical instruments which includes a key bed and a key frame mounted thereon, a series of levers extending transversely of 55 the bed and pivotally connected thereto, said levers being movable between the frame and bed, said bed including longitudinal bars, rods connected to said levers and extending parallel with said bars, a plurality 60 of shafts supported between the bars and extending transversely of the bed, bell cranks mounted on said shafts, rods connecting said levers with said bell cranks, said levers having portions which extend 65 below the bed, means having an operative connection with the mechanism to be controlled, and an operative connection between the portions of said bell cranks which extend below the bed and said means whereby 70 actuation of the levers will operate the mechanism to be controlled.

3. A controlling mechanism for self-playing 75 musical instruments which includes a key bed, a key frame arranged above the bed, 80 a plurality of levers pivotally supported on the bed and operating between the bed and frame, rock shafts supported by the frame and having an operative connection with said levers, a plurality of vertically extending 85 rock shafts having an operative connection with the first mentioned rock shafts, said rock shafts at their upper terminals having crank arms and rods engaging said crank arms and having an operative engagement 90 with the mechanism to be controlled.

In testimony whereof I affix my signature in presence of two witnesses.

RICHARD A. LEADBETER.
